UNITED STATES PATENT OFFICE.

JOSEPH GOMEZ, OF JACKSONVILLE, ILLINOIS.

SWING.

1,097,712.

Specification of Letters Patent.

Patented May 26, 1914.

Application filed May 3, 1913. Serial No. 765,288.

To all whom it may concern:

Be it known that I, JOSEPH GOMEZ, a citizen of the United States, residing at Jacksonville, in the county of Morgan and State 5 of Illinois, have invented certain new and useful Improvements in Swings, of which the following is a specification.

This invention relates to a combined porch or lawn swing and cot and has for its object 10 the provision of a device of this character which is so constructed that it may be readily converted from one form to the other.

An important object is to provide a device 15 of this character the seats of which are so constructed that they may be swung from the chair position to a cot-forming position and maintained in either position without the necessity of removing any bolts, screws, 20 or the like, which may be shifted individually, and which may also be adjusted to different angular positions.

A further object is to provide a device of 25 this character which may be easily set up or taken down for storage or shipment by the removal of a minimum number of bolts.

Other objects such as simplicity, comfort, 30 cheapness, efficiency, durability and the general improvement of the art will be fully brought out in the following specification and illustrated in the accompanying drawings, in which:

Figure 1 is a side view of the device partly in section, one side being shown in 35 its upright position and the other side being shown in its horizontal position, Fig. 2 is an end view, and Fig. 3 is a disjointed view of a hanger for pivoting the swing upon the frame.

Referring more particularly to the drawings the numeral 1 designates longitudinally 40 extending bars which are rounded upon the ends as shown at 2, and which are connected by transverse bars 3. Secured upon the bars 45 1 adjacent the bars 3 are upright bars 4 which are braced by bars 5 and 6 which are connected with the transverse bars 3 and the bars 1, respectively, as shown at 7 and 8. Upon their upper ends the bars 4 are provided 50 with metallic sockets 9 which are bolted or otherwise secured thereto and which comprise a top plate 10, side plates 11 and 12 and an upstanding lug 13 provided with a recess 14 for a purpose to be described. The swing is disposed within this 55 frame work just described and is adapted

to be pivoted upon the brackets 9. The swing portion comprises upright bars 15 connected at their lower ends by transverse rods 16. The floor or base portion consists of 60 longitudinal bars 17 provided adjacent their ends with recesses 18 adapted to engage the transverse rods 16. A plurality of slats 19 are secured transversely upon the bars 17. At their upper ends the vertical bars 15 are 65 provided with brackets 20 which comprise horizontal and vertical plates 21 secured upon the bars 15 as by means of bolts or screws, and which further comprise laterally extending trunnions 22 adapted to seat 70 within the recesses 14 in the brackets 9. It will be seen that thus the swing portion is pivotally supported on the uprights 4, and that it may be easily and quickly removed from the main frame work by lifting it 75 sufficiently for the trunnions 22 to become disengaged from the sockets 14.

Pivoted upon rods 23 extending transversely of the bars 15 are slatted-seat portions 24 to which are pivotally connected, as 80 at 25, bracing legs 26 recessed at their lower ends, as shown at 27, and connected by brace rods 28. Slatted back rests 29 are also pivoted upon the rods 23. Arms 30 provided upon their ends with pins 31 are 85 pivotally connected with the back rests 29 as shown at 32. Secured upon the seat portion 24 are upright arms 33 which are provided upon their free ends with pins 34 adapted to engage recesses provided adjacent the free ends of the arms 30. 90

The operation of the device is as follows: Referring to the showing on the right hand side of Fig. 1 of the drawings it will be observed that the seat portion 24 and the 95 back rest 29 are in position for use as a chair. In this position the various arms and supporting legs are arranged as shown, that is to say, the legs 26 extend vertically downward and the notches 27 engage the 100 first of the slats 19, the arms 30 extend in a substantially horizontal direction and the arms 33 have their pins 34 engaged within the recesses in the arms 30. Referring to the left hand side of Fig. 1 it 105 will be seen that the seat 24 and back rest 29 are arranged in a horizontal position, whereupon the various arms and supporting legs will be disposed as shown. This change is effected by pulling upwardly 110 upon the arms 30 to disengage the recesses in the arms 30 from the pins 34 formed on

the arms 33, lifting the seat portion 24 so that the notches 27 in the legs 26 will disengage the slats 19, swinging the back 29 downwardly toward the center of the swing 5 until it is in a horizontal position and the pins 31 engage the apertures 35 formed in the slats 19, and swinging the seat 24 downwardly and outwardly until it is in a horizontal position and so disposing the legs 26 10 that the notches 27 will engage pins 36 disposed upon the inner sides of the upright bars 15.

When the device is in the position shown in Fig. 1, one chair may be occupied by 15 one person in a sitting position while a child, for instance, may be lying upon the other chair which has been converted into a cot. It will be understood that by shifting the other back 29 and seat 24 into a horizontal position, as shown at the left of Fig. 20 1, the entire swing may be converted into a complete cot.

Referring again to the left of Fig. 1, if it is desired to form an elevated end on the 25 cot it is merely necessary to shift the legs 26 from engagement with the pins 36 and into engagement with the pins 37 whereupon the seat 24 will be elevated as shown by the dotted lines.

30 It will be readily seen that the swing portion may be lifted out of engagement with the brackets 9 on the main frame and collapsed by lifting the bars 17 out of engagement with the rods 16, and that the 35 main frame itself may be taken down by removing the bolts 7 and 8 and lifting the bars 4 out of their sockets in the bars 1.

Having thus described my invention what I claim is:

40 1. A convertible swing and cot comprising a stationary frame, a swinging frame suspended therefrom, seats mounted on said swinging frame, said seats comprising horizontal and vertical portions pivoted upon 45 said swinging frame, arms pivoted upon

said horizontal and vertical portions and adapted to engage portions of said swinging frame, said vertical portions being adapted to be lowered inwardly into a horizontal position, and said horizontal portions being adapted to be swung downwardly and outwardly into a horizontal position. 50

2. A convertible swing and cot comprising a stationary frame, a swinging frame pivotally connected therewith, said swinging frame comprising upright members, and a floor connected therewith, seats connected with said swinging frame, said seats comprising horizontal and vertical portions pivoted upon said upright bars, brace-rods 55 connected with said horizontal portions and adapted to engage said floor, arms pivoted upon said vertical portions and adapted to engage arms upon said horizontal portions, said vertical portions being adapted to be lowered into a horizontal position, and said horizontal portions being adapted to be swung downwardly and outwardly, said brace-rods being adapted to then engage pins upon said swinging frame, and said 60 pivoted arms being adapted to engage said floor. 65

3. A convertible swing and cot comprising a stationary frame, a swinging frame pivotally connected therewith, seats mounted upon said swinging frame, said seats comprising pivoted seat and back portions, said back portions being adapted to be swung inwardly into a horizontal position, and said seat portions being adapted to be 70 swung downwardly and outwardly into a horizontal position, and braces for maintaining said back and seat portions in either position. 75

In testimony whereof I hereto affix my 85 signature in the presence of two witnesses.

JOSEPH GOMEZ.
